UNITED STATES PATENT OFFICE.

LEE EVANS, OF RED LAKE, NEW MEXICO.

STOCK-GUARD.

1,359,974.

Specification of Letters Patent. Patented Nov. 23, 1920.

Application filed July 22, 1920. Serial No. 398,170.

To all whom it may concern:

Be it known that I, LEE EVANS, a citizen of the United States, residing in the city of Red Lake and State of New Mexico, have 5 invented new and useful Improvements in Stock-Guards, of which the following is a specification, reference being had to the accompanying drawings.

This invention pertains to stock guards 10 for wagon roads, and the object is to provide a simple and efficient apparatus for installation on vehicle roads, in lieu of gates, and which will permit the ready passing of vehicles or horses, as desired; while preventing the passage of cattle or other stock 15 when not desired.

In the drawings:

Figure 1 is a plan view.

Fig. 2 is a side elevation.

Fig. 3 is an end elevation.

Fig. 4 is a detail of the latch mechanism for locking the triangular guards in flat position for the passing of a vehicle.

Fig. 5 is a detail of the spring for holding 25 the guards in pointed position for preventing the passing of stock.

The invention consists of a plurality of triangular bars 1, which are pivoted by means of the center pins 2 transversely between the sills 3. A control rod 4 is laid along the series of bars, at one side thereof, and this rod is loosely pinned to the points 5 of the bars by means of linked staples 6. Thus as the rod 4 is moved endwise in either 35 direction, the result is to throw the sides 7 of the bars 1 upwardly into horizontal relation and so as to present a uniform flat surface for the passage of vehicles. A spring 8 normally holds the bars with the points 5 in vertical position for preventing the passing 40 of stock. A lever 9 is pivoted at one end 10 to the control rod 4 and at the other end

11 to one of the sills 3. Hand levers 12 are likewise pivoted at 13 and 14 to said rod and sill. A latch 15 is provided to hold the lever 45 9 in its position drawn against the spring 8. Cables 16 extend from the hand levers 12 over pulleys 17 to the latch 15 as means for raising the latch and permitting the bars to assume their vertical position after the 50 vehicle has passed over.

By manipulating either of the hand levers 12 the flat sides 7 of the bars are turned up, and the latch 15 falls over the lever 9, thus holding the bars in said position. 55 After the vehicle passes over, by pulling upon either of the cables 16, the latch 15 is raised and the spring 8 draws the bars back into position with points 5 upward, the position required for preventing stock passing 60 over.

While I have herein described a certain specific method of constructing and assembling the elements of my invention, it is understood same may be varied in minor 65 details, not departing from the spirit of my invention as defined in the appended claim.

What I claim to be new and patentable is:

A stock guard comprising two horizontally spaced sills; a plurality of triangular 70 bars pivotally and transversely mounted between said sills; a control rod linked to the points of said bars; hand levers, one at each end, for manipulating said control rod; a spring for normally holding said control rod 75 back in order to turn the points of the bars upward; and a releasable latch mechanism for holding said control rod in its strained position in order to turn the flat sides of the bars upward.

LEE EVANS.
